UNITED STATES PATENT OFFICE.

HANS PETERSEN, OF DAVENPORT, IOWA, ASSIGNOR TO THE LINOGRAPH COMPANY, OF DAVENPORT, IOWA, A CORPORATION.

TYPOGRAPHICAL MACHINE.

1,385,585.

Specification of Letters Patent. Patented July 26, 1921.

Application filed February 27, 1920. Serial No. 361,880.

To all whom it may concern:

Be it known that I, HANS PETERSEN, a citizen of the United States, and a resident of Davenport, in the county of Scott and 5 State of Iowa, have invented certain new and useful Improvements in Typographical Machines, of which the following is a specification, reference being had therein to the accompanying drawing.

10 This invention relates to improvements in typographical machines, and more especially has to do with the improved manner of and means provided for alining the matrices against the face of the mold during 15 the casting of the line therefrom.

A great majority of line casting machines now in use employ what is known in the trade as two-letter matrices. These matrices are provided with two depressed characters 20 in one of their faces, said characters being spaced a certain distance apart. The matrix assembling devices are provided with two assembling rails, on either one or both of which the matrices are adapted to be assembled before being advanced to casting position. If the assembled matrices are carried 25 to the casting position in front of the mold on the lower level, the result will be that as the mold advances toward the matrices, the

30 lower alining groove on the face of the mold will coöperate with the lower lugs of the matrices and aline the upper characters against the face of the mold opposite the mold cavity, and the line will be cast from the upper series of characters on the 35 matrices. On the contrary, if the line of matrices is presented in front of the mold assembled on the upper rails, they will be engaged by the upper alining slot or groove 40 in the mold and the cast will be made from the lower series of characters.

On practically all of the machines now in use two-letter matrices are employed in which the two characters are spaced such a 45 distance apart that a font of type larger than what is commonly known as 14 point, cannot be accommodated on the matrix in the lower level. As all two-letter characters must necessarily be of the same height as 50 they occur on the same matrix, this, for all practical purposes limits both of the characters to a size not exceeding 14 points in height.

The object of the present invention is to

provide an improved machine of the nature 55 referred to that permits of a much wider range as regards the size of character of two-letter matrices employed, the difficulties hereinbefore referred to being entirely avoided and the usefulness of the machine 60 being increased to a considerable extent.

A further object of the invention is to improve the construction of such machines to permit the casting of a larger slug than has heretofore been possible with the present 65 standard construction of the essential parts of the mold, and from the present standard form of matrix.

The invention comprehends the use of two-letter matrices and coöperating two-letter 70 mold of standard form, said matrices having characters larger in size than that of the characters on 14 point font of type, say, for example, 24 point height, and which may be used with the so-called 14 point two-letter 75 matrices in the same machine having elevator mechanism of general standard form.

The present application is to be considered as a continuation of my application, Serial No. 250,728, filed August 20, 1918, in so far 80 as the subject matter is common to both cases.

The invention, with other objects and advantages thereof, and the particular constructions, combinations and arrangement of parts comprising the same, will be understood from the following detailed description, when considered in connection with the accompanying drawings forming part hereof and illustrating one embodiment of the invention. 90

In the drawings:

Figure 1 is a side elevation of a mold carrying wheel equipped with a series of molds in accordance with the present invention. 95

Fig. 2 is a transverse section on the line 2—2 of Fig. 1 through the upper mold on the wheel showing in side elevation at the left of the mold structure matrices adapted to coöperate therewith. 100

Fig. 3 is a transverse section through another mold on the wheel showing to one side thereof in side elevation two-letter matrices having characters of larger size and adapted to coöperate with the same. 105

Fig. 4 is a front elevation of an elevator body.

Fig. 5 is an end view of the elevator body.

Fig. 6 is a transverse section on the line 6—6 of Fig. 4.

Fig. 7 is a detail side elevation of one of the matrices adapted to coöperate with the 5 mold A; and

Fig. 8 is a detail side elevation of one of the matrices adapted to coöperate with the mold B.

Referring to a detailed description of the 10 drawings, wherein like reference characters designate corresponding parts throughout the several views, 1 designates the mold wheel having a two-letter matrix mold A consisting of the body part 2 and cap 3, the 15 mold cap having a forwardly projecting part 3'. The body part 2 of the mold has upper and lower alinement grooves 4 and 5, and 6 designates two-letter matrices, all as 20 customarily employed in the usual form of line casting machine.

In accordance with the present invention, on the mold wheel 1 is mounted another mold B comprising a body 7 and a cap 8, the latter having a forwardly projecting portion 8'. The mold B may be brought to casting position at will, and is adapted for use in coöperation with two-letter matrices 9, which bear characters of greater height and spaced a different distance apart than 25 the characters on the matrices 6 that are used with the mold A, said mold B being provided with upper and lower alinement grooves 10, 11. It will be noted that the 30 alinement points for the upper character on both sets of matrices 6 and 9 are in the same relative position, but that in the case of the matrices 9, the characters extend a greater distance in both directions from this common point than they do in the matrices 6. 35 12 designates the front elevator jaw having the stationary rail or shoulder 13 for supporting the matrices at their lower level, 14 the back elevator jaw, and 15 the spacing block for the jaws. The molds A and 40 B, the essential parts of both of which, as shown, are of the standard construction, are adapted to coöperate with the elevator jaws 12, 14 in the usual manner, the forwardly extending portions 3' and 8' of the respective 45 molds extending beneath the lower end of the back elevator jaw 14 in the casting operation. In Fig. 2 of the drawings, the mold A is shown opened to its fullest extent of 14 points, which is the maximum size of the 50 character and slug now cast with the standard typographical machine from the normal alinement level of the standard matrix.

In accordance with the teachings of the 60 present invention, the construction of the back elevator jaw 14 is changed as shown, (see especially Figs. 5 and 6 of the drawings) the usual alinement rail being omitted and the lower end 14' of the jaw terminating 65 on the plane of the bottom face of the upper lugs of the matrix when in its lower

level, provision thus being made for the adjustment of the mold cap 8 vertically a greater distance away from the mold body 7 and the opening of the mold to a greater extent. For this purpose the forwardly 70 projecting portion 8' of the cap 8 is also reduced in size to the minimum practical thickness.

A vital characteristic of the invention resides in providing the mold B with its upper alinement groove 10 of greater width than the corresponding alining groove 4 in the other mold A. This additional height is added at the under side of the groove and the action when the cast takes place 80 is as follows: When it is desired to make a cast from the matrices 9 carrying the larger characters, the mold wheel 1 is given a half turn and the mold B is brought into casting position. As the line of matrices 85 advances to casting position, they are first permitted to descend to a point a little below the final casting position. The mold is then brought forward and engages the lower lugs of the matrices, the line of matrices being then raised by a flexible pressure mechanism (not shown) to a contact with the lower edge of the alinement groove 11. In the case of the set of matrices 9 carrying in their auxiliary position the 90 larger characters, the flexible pressure would result in the line of matrices rising a greater distance until they contact with the lower edge of the alinement groove in the mold, thus exposing the character to the 100 mold slot *a* at a different level than is the case when the matrices 6 are presented to the mold A.

It will be observed that this method of handling the matrices contemplates casting 105 from the matrices 6 on both levels mixed in the same line, but from only one of the levels at the same time in the case of the set of matrices 9. If only one level of the larger matrices 9 is presented to the mold B 110 at the same time, the usual non-adjustable supporting means (commonly known in the trade as elevator jaws) may be employed. If it is desired to mix the two faces carried by the matrices bearing the larger characters in the same line, it will be necessary to employ an adjustable variable matrix supporting device to present the matrix at levels corresponding to the distance which the two characters are spaced apart on the 115 matrix. The means for this purpose, illustrated in the drawings, comprises the following parts: Instead of the usual single two-letter rail, two separate rails 15', 16 are employed, the rail 15' at its entrance end 120 being provided with the tapered part 15'. The rails 15', 16, are operated respectively by pairs of levers 16', 17, said levers being held in their normal positions for supporting the matrices by springs 18. A pair of 130

cams 19 adapted to be operated by a handle 20 are provided for holding the rail 15' out of action when desired.

When casting from the matrices 6, not exceeding substantially 14 point in size, the matrices are supported in their lower or normal position by the upper ears on the stationary shoulder or rail 13, and in their upper or auxiliary position by the rail 16.

10 When it is desired to make a cast from the matrices carrying sizes larger than 14 point, in which case it is necessary to space the matrix recesses farther apart on the matrix, the handle 20 is raised, operating the cam 19 and permitting the levers 16' to draw the rail 15' into action. When the rail 15' is brought into operative position in the path of the matrices, they will slide up on the tapered part 15² to a higher and third level, 20 and so coöperate with the mold B, which is constructed to provide for the alinement of the matrices at three levels.

Now, when the matrices are advanced into the elevator jaw, the auxiliary matrices will 25 be carried at a higher level, alining the lower character on these matrices with the upper character on those carried in their normal position on the rail 13, and in this way the larger matrices are presented to the mold B 30 with the faces resting in the same line in the same manner as the matrices bearing smaller characters are presented to their mold A when the rail 15' is held out of action.

35 While I have illustrated in the drawings a specific embodiment of the invention, it will of course be understood that changes and variations in the particular construction shown, and the carrying out of the invention in other forms as will appeal to those skilled in the art and falling within the scope of the appended claims, may be practised without departing from the spirit of the invention.

45 What I claim is:

1. In a typographical machine, the combination with means for composing two-letter matrices on two levels, of means for casting lines from the matrices at more than 50 two fixed levels, said means including two molds, the molds having pairs of alinement grooves, one of the alinement grooves of one mold being of a different depth and having its upper wall extending at a different level 55 from the corresponding alinement groove of the other mold.

2. In a typographical machine, means for casting lines from matrices at three fixed levels, said means including two molds, the 60 molds having pairs of alinement grooves, one of the alinement grooves of one mold being of a different depth and having its upper wall extending at a different level 65 from the corresponding alinement grooves of the other mold.

3. In a typographical machine, a series of molds, and sets of two-letter matrices, with similar alinement at one level for one series of faces and variable alinement at other levels for another series of faces, in 70 combination with a support and coöperating parts on said support and the molds for the alinement of the matrices at two or more levels.

4. An assembling mechanism for assembling matrices at two levels, in combination with a carrier for casting at three levels. 75

5. An assembling mechanism for assembling matrices at two levels, in combination with a carrier for casting at three levels, 80 said carrier including an adjustable rail member provided with a tapered entrance end part.

6. In a machine of the class described, adjustable two-letter rails permitting two-letter matrices to be alined at two or more levels. 85

7. In a machine of the class described, adjustable two-letter rails permitting two-letter matrices to be alined at two or more levels, operating means for said rails, and means for maintaining one of the rails out of operation. 90

8. In a machine of the class described, matrices of standard size having standard 95 spaced alinement lugs and provided with characters of a height substantially greater than the height of the characters on the standard matrix, elevator mechanism including a front elevator jaw with the usual ledge 100 for supporting the matrix at the lower level, and a back elevator jaw, the lower end of which terminates short of the space below the bottom face of the upper lugs of the matrix when in its lower level, and a standard 105 type of mold comprising a mold body having alinement grooves and a cap having a forwardly projecting part adapted to extend beneath the lower end of the elevator jaw, the mold cap being adjustable vertically relatively to the mold body to vary 110 the height of the mold cavity.

9. In a machine of the class described, matrices of standard size having standard 115 spaced alinement lugs and provided with characters of a height substantially greater than the height of the characters on the standard matrix, elevator mechanism including a front elevator jaw with the usual ledge for supporting the matrices at their 120 lower level, and a back elevator jaw, the lower end of which terminates level with the bottom face of the upper lugs of the matrix, when in its lower level, and a standard 125 type of mold comprising a mold body having alinement grooves, and a cap having a forwardly projecting part of minimum thickness adapted to extend beneath the lower end of the elevator jaw, the mold cap being adjustable vertically relatively to the 130

mold body to vary the height of the mold cavity.

10. In a machine of the class described, matrices of standard size having standard spaced alinement lugs and provided with characters of a height substantially greater than the height of the characters on the standard matrix, elevator mechanism including a front elevator jaw with the usual ledge for supporting the matrices at their lower level, and a back elevator jaw, the lower end of which terminates short of the space below the bottom face of the upper lugs of the matrix when in its lower level,
- 15 and a standard type of mold comprising a mold body having alinement grooves, and a cap having a forwardly projecting part of substantially less thickness than the thickness of said part in the standard size of mold
- 20 adapted to extend beneath the lower end of the elevator jaw, said mold cap being adjustable vertically relatively to the mold body to vary the height of the mold cavity.

11. In a typographical machine, a series 25 of molds and sets of two-letter matrices with similar alinement at one level for one series of faces and variable alinement at other levels for another series of faces, in combination with a support, and adjustable two-letter rails on the support providing for the alinement of the two-letter matrices at two or more levels.

12. In a typographical machine, the combination of a series of molds, a set of two-letter matrices for coöperating with each of the molds, the different sets of matrices having differently spaced characters, the molds having pairs of alinement grooves, one of

the alinement grooves of one mold being of different depth than the depth of the corresponding alinement groove of another of the molds, the matrices of all the sets for one series of characters having similar alinement at one level, and having variable alinement at other levels for another series of characters during the molding operation, a support and adjustable two-letter rails on the support providing for the alinement of the two-letter matrices at two or more levels.

13. In a typographical machine, the combination of different sets of matrices having differently spaced characters, a support, two-letter rails on the support adjustably mounted for movement into and out of operative position and providing for the alinement of the two-letter matrices at a plurality of levels, and operating means for the rails.

14. In a typographical machine, the combination with different sets of matrices bearing characters of different height, a support and two-letter rails adjustably mounted on the support for movement into and out of operative position and providing for the alinement of the two-letter matrices at two or more levels, and operating means for the rails including means acting to move the rails to operative position with means for maintaining one of the rails out of operative position.

In testimony whereof I hereunto affix my signature in the presence of two witnesses.

HANS PETERSEN.
